COLLAR POINT STAY

John F. Florkiewicz, Oakland, Calif.

Application January 10, 1948, Serial No. 1,601

4 Claims. (Cl. 2—132)

1

The invention relates to stiffening stay elements for installation at the point portions of relatively soft turn-down shirt collars.

An object is to provide a collar-point stay of the character described which may be removably fixed to a mounting collar edge in a particularly effective self-retaining manner.

Another object is to provide stay elements which may be independently mounted on the point portions of a collar.

A further object is the provision of collar-point stays of the character described which are arranged to carry decorative elements in front of collar point portions which mount them.

An added object is to provide for a cooperative connection of a pair of the installed stays by a separable means which may be more or less ornamental.

Yet another object is to provide collar-point stays of adjustable length.

The invention possesses other objects and features of invention, some of which, with the foregoing, will be set forth or be apparent in the following description of typical embodiments thereof, and in the accompanying drawings, in which

Figure 1 illustrates a cooperative pair of one embodiment of the stays as installed on the front end or point portions of a turned-down collar of a shirt.

Figure 2 is a rear-side view of the installed right-hand collar-point stay shown in Figure 1.

Figure 3 is an enlarged longitudinal section taken through the stay of Figure 2.

Figures 4 and 5 are enlarged sections taken respectively at the lines 4—4 and 5—5 in Figure 2.

Figure 6 is a perspective exterior view of the left-hand stay 30 shown in Figure 1.

Figure 7 illustrates the installation of a cooperative pair of another embodiment of the stays on the point portions of a turned-down collar of a shirt.

Figure 8 is a rear-side view of the installed right-hand collar-point stay shown in Figure 7.

Figures 9 and 10 are enlarged sections taken respectively at the lines 9—9 and 10—10 in Figure 8.

Figure 11 is an enlarged and rear perspective view of the left-hand stay of Figure 7.

Figure 12 is an enlarged and front perspective view of the left-hand stay of Figure 7.

As particularly illustrated in Figures 1 to 6, similar and mutually complementary unitary stays 18 and 19 embodying my invention are mounted at the right-hand and left-hand front end point or wing portions 20 and 21 of a rela-

2

tively soft fabric collar 22 which extends from the neckband 23 of a shirt 24, the shirt having a buttoned neckband and front. As is usual, the collar 22 comprises outer and inner plies of fabric 25 and 26 respectively, said plies being sewed together at customarily inturned edge portions to provide hems 27 and 28 of four-ply thickness at the free front end and bottom edges of the collar, respectively. A necktie will usually be mounted on the closed shirt front, a four-in-hand tie 29 being shown.

The present stays 18 and 19 have mutually reversed parts whereby they are arranged for mounting respectively on the mutually opposed right- and left-side end portions 20 and 21 of the collar. Except for the mutually reversed arrangement of their parts, the stays 18 and 19 are similar and essentially comprise stem or shank portions 31 provided with spring slip members 32 and sharpened prongs 33 at opposite ends thereof.

In the present structure, each clip 32 comprises a return bend of spring wire or the like fixed to the shank near its top and disposed in a plane 25 which is perpendicular to the stem axis, and has a side or leg 32' extending radially from the shank and a side or leg 32'' terminating opposite and slightly beyond the shank. The spring clip thus provided is arranged to frictionally receive and grip an upper part of a front collar edge with the leg 32'' against the outer face of the collar for clamping the collar point against the shank thereat. If desired, the clip portion 32'' may carry an ornamental element 34; in the present instance, the element 34 is provided at the free end and front side of the clip portion 32'' whereby it does not affect the grip provided between the clip portion 32'' and the shank.

The like prongs 33 of the stay pairs are laterally offset from bottom shank portions, each prong having a pointed straight portion 33' directed downwardly from a connecting portion 33'' which extends generally radially as an arm from a bottom point of the shank 31 in fixed relation thereto. A prong portion 33'' may be generally S-shaped, as shown, whereby to provide an acute angle bend 35 between the prong portions 33' and 33''. The sharpened prong portion 33' is arranged for insertion longitudinally downwardly within the hem 27 from the back of the collar point and to a degree determined by the engagement of the prong bend 35 with the fabric at the point of entry of the prong. The prong 33 is preferably disposed in coplanar relation with the side 32' of the clip 32 and extends from the

same side of the stem axis whereby the stem may be disposed against the inner fabric ply 26 beyond the collar end hem 27 when a stiffener unit 18 or 19 is installed in the indicated manner; the shank and collar point combination may thus be of minimum thickness thereat.

While the shank and clip and prong portions of the stay might be integrally connected to provide a stay of fixed effective length, it may be desirable that the stays 18 and 19 be of adjustable length, with their shanks 31 having sections which are mutually adjustable in the shank line. In the present structure, each clip 32 comprises end portions of a length of resilient wire which is formed to provide a return bend 37 having one leg 37' extending upwardly and integrally from the inner end of the clip portion 32' as the attaching means therefor and having its other leg 37'' straight and somewhat longer than its side 37'. Intermediately thereof, the wire portion 37'' is slidably and frictionally engaged in the bore of a tubular element 38 which carries the prong 33 fixed thereto; in the present structure, the prong 33 is shaped of a length of wire and has a base portion 33''' extending along and fixed to the exterior of the lower portion of the tube 38 whereby the tube and prong unit thus provided are adjustable along the wire portion 37''.

Means may be provided to increase the rigidity of a present stay 18 or 19 at its bend 37. As particularly shown, a tubular element 39 slidably receives the tube 38 in its bore, extends from the top of the bend 37 and is fixed to the bend side 37' at the point of the bend as by soldering or welding. The upper end of the tube member 39 is arranged to be and remain frictionally engaged in the bore of the tube 38 as the effective length of the stem 31 is adjusted, and the arrangement is understood to stiffen the bend side 37' against undue flexure during its installation and use.

At its lower end below the tube 38, the wire portion 37'' is provided with a loop 41 which acts as a stop thereto for preventing an accidental removal of the tube 38 from its adjustably mounted position on the wire portion 37''. In the present structure, the loop 41 also comprises an eye at which the ends of a flexible connection 42 may be secured, said connection comprising a chain assembly releasably connecting the eyes 41 of the units 18 and 19. As particularly illustrated, the chain 42 has sections 42' and 42'' which connect the eyes 41 of the different stays with the different elements of a separable member 43 of more or less ornamental form for disposal in front of or behind the necktie 29; the present member 43 comprises sections 43' and 43'' of hemispherical outline which respectively provide the elements of a ball and socket connection between them.

It will now be particularly noted that the present stays 18 and 19 may be adjustably mounted on the collar of a shirt while they are mutually free, and either before or after the shirt is donned by a wearer. In mounting a stay 18 or 19, its prong 33 is fully inserted from the rear in the appropriate hem 27 while the shank 31 extends along the hem with the clip 32 adjacent but free of the hem, after which the stay is swung about the point of engagement of the prong bend 35 with the inner collar ply 26 for effecting a relatively positive gripping of the hem by the clip; in this manner, the mounting of each stay may be effected while leaving the collar point in smooth condition between the prong and clip and disposing the shank of the stay inwardly of the thicker portion of the collar point at the hem 27.

While the shirt is donned and has been closed at its upper front as provided for, the chain sections 42' and 42'' of the mounted stays 18 and 19 may be connected, as by the separable member 43 disposed either in front of or behind the necktie 29 as desired. It will be understood that the connecting chain 42, particularly if extended behind the necktie, may serve to generally anchor the stiffened collar points against their outward swinging from their normal position against the shirt front. It will also be understood that the stays 18 and 19 may remain in their mounted positions on the collar ends if the shirt is to be worn more than once, the chain 42 being opened 15 during a removal or donning of the shirt.

Figures 7 to 12 disclose a pair of collar point stiffeners which are arranged for installation in an operatively inverted relation to a shirt collar as compared with the units 18 and 19. As shown, 20 stiffener units 48 and 49 are mounted at the front end portions, or points, 50 and 51 of a collar 52 which extends from the neckband of a shirt 54, the shirt having a buttoned front and neckband. The collar 52 has the structure of the 25 collar 22, and is formed with outer and inner plies of fabric 55 and 56 which are sewed together at customary inturned edge portions to provide hems 57 and 58 at the free front and bottom edges of the collar respectively. A necktie 59 30 of the four-in-hand type is shown as mounted at the front of the shirt and generally between the collar points 50 and 51.

The stiffener units 48 and 49 are arranged for mounting respectively on the right and left side 35 end points 50 and 51 of the collar 52, said units having their parts in mutually complementary relation to provide for their like application at the different collar edges. Except for the mutually reversed relation of certain of their parts, 40 the stiffener units 48 and 49 essentially comprise stem or shank portions 61 provided with spring clips 62 and prongs 63 at opposite ends thereof, and are of fixed, rather than adjustable, length. In terms of its disclosed mounted position, each 45 clip 62 comprises a U-bend extending from the shank near its bottom, and has a side 62' extending radially from the shank and a side 62'' extending opposite and slightly beyond the shank. The clip thus provided is arranged to frictionally 50 receive and grip the lower part of a front collar edge with the side 62'' against the outer face of the collar. The clip portion 62'' may carry an ornamental element 64 at its free end.

The prongs 63 of the units 48 and 49 are laterally spaced from upper stem portions, and have pointed straight portions 63' directed downwardly from connecting portions 63'' which extend generally radially from the shanks 61 in fixed relation thereto. In the present structure, 55 each sharpened prong portion 63' is arranged for insertion longitudinally downwardly in a hem 57 from an upper point at the back of the collar and to a degree determined by the engagement of the prong portion 63'' with the fabric at the point of entry of the prong. It is to be noted that the prong 63 is disposed in coplanar relation with the side 62' of the clip 62 and extends from the side of the shank axis whereby the shank 61 may be disposed against the inner fabric ply 56 beyond the collar-point hem 51 when a stiffener unit 48 60 or 49 is installed in the indicated manner, whereby the shank and collar point combination may be of minimum thickness thereat.

In the present structure, an eye 71 is provided on the shank 61 below the clip 62; said 75

eye being defined within an open return bend 70 at the bottom of the shank and having the clip portion 62' extending from the upper end of the bend side 70' which extends laterally of the stem. The return bends 70 of cooperative units 48 and 49 serve to extend the stiffening action of the shanks 61 beyond the clips 62 and they also may be utilized as terminal anchorages for flexible connections such as the chain 42 disclosed in connection with the units 18 and 19 of the first embodiment.

It is to be noted that the present units are generally hung from upper points of the hems 57 of the connecting bends at the tops of the prongs 63", whereas the prongs 23 of the first embodiment generally seat the units on the bends 35 at the tops of the prongs 33. Also, since the present stiffener units 48 and 49 lack any provision for length adjustments thereof, the stay shank and clip and eye and prong portions may comprise, as shown, parts of a single strip of wire to provide a particularly simple structure for its purpose.

From the foregoing description taken in connection with the accompanying drawings, the advantages of the present collar point stay features will be readily understood by those skilled in the art to which the invention appertains. While I have described arrangements which I now consider to be the preferred embodiments thereof. I desire to have it understood that the showings are primarily illustrative, and that such changes and developments may be made, when desired, as fall within the scope of the following claims.

I claim:

1. In a unitary collar-point stay of the character described, a shank arranged for its removably mounted disposal behind and against the front edge portion of a turn-down collar point as a stiffening means therefor, a sharpened prong arranged for its insertion within the collar point structure in coplanar relation therewith and carried by the shank in laterally offset parallel and coplanar relation thereto at the end of an arm extending radially from the shank adjacent an end thereof and operative to limit the degree of insertion of the prong within the engaged collar point, a collar-gripping portion including a spring arm extending transversely of and across the shank adjacent the other end thereof and operative in the common plane of

the prong and arm to directly receive and grip a front collar edge between it and the shank while the prong portion of the stay is operatively engaged in the collar point, and means on the shank in its axial line providing an eye arranged for the attachment thereto of a flexible connecting means between the stay and the corresponding eye of a complementary like stay mounted on the other collar point.

2. In a unitary collar-point stay of the character described, a shank portion of uniform cross-section arranged for its removably mounted disposal behind and along the front edge portion of a turn-down collar point, a sleeve member slidably and frictionally receiving therethrough said shank portion for its adjusted positioning therewith, a prong carried by the sleeve member in laterally offset parallel and coplanar relation thereto at the end of a radial arm extending appreciably from the section and arranged for its insertion within and along the collar edge portion to a limit imposed by the arm, and a collar-gripping spring clip comprising an integral extension of said shank portion and arranged to grippingly receive a front collar edge while the point portion of the stay is operatively engaged in said edge.

3. A structure in accordance with claim 1 wherein the connection eye is provided at the prong end of the shank.

4. A structure in accordance with claim 1 wherein the connection eye is provided at the same end of the shank as the collar-gripping portion.

JOHN F. FLORKEWICZ.
